UNITED STATES PATENT OFFICE.

GEORGE W. GRAVES, OF TROY, NEW YORK, ASSIGNOR OF ONE-HALF TO
CHARLES E. POTTER, OF SAME PLACE.

DESIGN FOR A HEATING-STOVE.

SPECIFICATION forming part of Design No. 12,288, dated May 31, 1881.

Application filed July 14, 1880. Term of patent 7 years.

To all whom it may concern:

Be it known that I, GEORGE W. GRAVES, of the city of Troy, county of Rensselaer, and State of New York, have invented a new and 5 useful Improvement in Ornamental Designs for Heating-Stoves, of which the following is a specification.

My invention of a design relates to the ornamental form and surface ornamentation of a 10 heating-stove and the several parts thereof; also, to the application of a colored surface to the magazine-section, and the combination of a colored thermometer with a nickel-plated standard upon the dome-formed top of the stove, 15 as shown in the annexed photograph, forming a part of this specification.

My invention of a design for the top of a heating-stove consists in the combination of the dome-formed top A and the surface ornamentation displayed thereon, consisting of the 20 upwardly-directed row of relief-points arranged in revolution around the base of the dome, as shown at a, the row of contiguous diamonds in relief around the crown of the dome, as shown at b, and the downwardly-projecting radiate points around the top of the dome, as 25 shown at c'. 70

My invention of a design for the ornamentation of the top of a heating-stove consists in 30 the form and ornamentation of the apex column B, it having the buttressed sides a'' a'' and downwardly-projected feet d' d' d' d', and which curve from the base at four points downwardly and oppositely along and in contact with the dome-surface to its base, as shown at c'' c'', 35 ornamented with the steps d'' d'' and the projecting fan radiate ornaments, (designated at e e,) with knobs upon the steps, as shown at g g.

My invention of a design, as applied to the 40 parts of a heating-stove, also consists in the manner of ornamenting the top of the dome above the magazine-section by means of the apex column B', its buttressed sides a'' a'', all of which are nickel-plated, and the thermometer B'', having for ornamental effect a red glass tube placed against the column and between the buttresses. 45

My invention of a design for the ornamentation of the parts of a heating-stove also consists in the combination of the hemispherical 50

dome A of the stove-top, with the base-band molding i i in revolution about the bottom of the dome, and the overhanging ring j j, having at its base the line of scallops k k, with the band-molding i and the overhanging ring j, 55 nickel-plated.

My invention of a design for the several parts of a heating-stove also consists of the application to the top of the magazine-section of the reversed ovolo molding O, arranged in 60 revolution around the magazine-section at its top, and the molding ornamented upon its upper and lower edges with the waving lines l l, and the molding nickel-plated.

My invention of an ornamental design for 65 the magazine-section of a heating-stove consists in combining with the gray granite color placed on the magazine-section C', and as shown at C'', the nickel-plated relief-panels m m, placed thereon. 70

My invention of a design for the ornamentation of the magazine-section of a heating-stove also consists in the combination of the granite color applied to the section by means of granite enamel, as shown at C'', the upper 75 reversed ovolo molding O, and the base-molding D, scalloped at k''. 75

My invention of a design for ornamenting the doors of the combustion-chamber section of a heating-stove (the section being designated 80 at E) consists in the manner of arranging and shaping the sash-bars which divide the doors into mica panes or lights for illumination by means of the horizontally-bent bars r', having a double-reversing ogee curve between, where 85 they join the vertical sides of the frame z z, near their centers, and the upright branching sash-bars r'', which divide above their cross-intersection of the horizontally-curved bars to form a branching V-shaped union with the top 90 of the door-frame z, with the latter curved to adapt itself to the contour of the stove at that point.

My invention of a design for ornamenting the combustion-chamber doors of a heating- 95 stove also consists in the manner of curving the horizontal sash-bars r' r', the manner of curving and branching the upright bars r'' r'', and vine-leaf projections upon the edges of the bars, as shown at W W W W. 100

My invention of a design for the ornamentation of the lower mica section of a heating-stove (designated at F) consists in the **U**-shaped form of the sash-bars, dividing the frame *z'* 5 into mica lights or panes, as shown at *r'*.

My invention of a design for the ornamentation of the doors of the lower mica section, F, consists also of the combination of the **V**-shaped sash-bars *r'*, dividing up the frame *z''* 10 into mica panes for illumination, with vine-leaf projections *r''' r''' r'''* arranged upon the sash-bars.

My invention of a design for a heating-stove consists, also, in the manner of ornamenting the fire-pot section (designated at S) by means of the zigzag row of relief-work, combined with fan-tracery at the top of the section, as shown at *x' x' x'*, the row of zigzag ornamentation combined with fan-tracery, (shown at the base 15 and designated at *x'' x''*), and the contiguous row of **Z**-shaped figures arranged intermediately to the rows of ornamentation at the top and bottom of the section, the intermediate work being designated at *x''' x'''*.

25 My invention also consists in the design for the form and ornamentation of the sectional foot-rail **H H H**, each section being arranged opposite the curtained side of base between where the side of the base joins the feet, and 30 having the straight top *o'* and drooping curtain line *o'' o''* upon its lower boundary, and pendent point *o''*, with a radiant crown produced with intaglio lines upon the curtained front near its bottom point, as shown at *n'''*, 35 and with an intaglio border-line and scroll-work upon its face, (shown at *t''*).

My invention of a design also consists in the manner of ornamenting the surface of the rearward extension of the exit-flue **K'** by means of 40 a central rosette and a surrounding ring with four radiate branching fans and four intermediate intaglio darts, the latter being arranged at right angles, as shown at *n''*.

I am well aware that the form of a flattened 45 cone is usually applied to ornament the tops of magazine-stoves, and that my improvement of a design upon this older form consists in substituting for the cone form that of a hemisphere or dome, which latter may be employed 50 as a separate feature of ornamentation without the apex column or surface ornamentation with which I illustrate it, and the ornamental effect produced by the form of the top would remain the same.

55 While I employ the red color of the thermometer-tube to produce an ornamental effect, I make no claim to the thermometer, functionally considered, or otherwise than as its red color in combination with the nickel-plated surfaces 60 adjoining produce an ornamental effect.

I am well aware that there is no invention in the application of the granite color to the magazine-section, considered alone, and my invention of an ornamental design in which it is 65 an element is limited to its combination with the nickel-plated relief-panels, (designated and illustrated at *m*), and the combination of the

granite color applied to the magazine-section and the nickel-plated moldings **O** and **D**, as 70 illustrated.

Having thus described my invention, what I claim, and desire to secure by Letters Patent, is—

1. The design for the ornamental form and surface ornamentation of a heating-stove top, 75 consisting of the hemispherical dome **A**, the upwardly-directed rows of points in relief, arranged around and upon the exterior surface of the dome at its base, as shown at *a'*, the row of contiguous diamond-form inclosures 80 upon the crown of the dome, as shown at *b*, and the row of radiate points in revolution upon and around the top of the dome, as designated at *c'*, and as shown and described.

2. The design for the ornamentation of the 85 stove-top, consisting of the dome-surface **A**, apex column **B**, arranged on the top of the latter and having the buttressed sides *a''*, with the downwardly-projected feet *d'*, ornaments *e*, steps *d''*, and knobs *g* upon the latter, as 90 shown and described.

3. The design for the ornamentation of the top of the stove-dome **A**, consisting of the nickel-plated apex column **B'** and its nickel-plated buttressed sides *a''*, with the red thermometer-tube **B''**, placed between two of the 95 buttresses, as shown and described.

4. The design for the ornamentation of a heating-stove top, consisting of the dome **A**, the base-band molding *i* in revolution around 100 the bottom of the dome, the overhanging ring *j* below the molding, with the ring having at its lower edge the row of scallops *k*, and the molding and ring nickel-plated, as shown and described.

5. The design for the ornamentation of the top of a heating-stove, and consisting of the dome **A**, the radiate-point ornamentation in revolution upon the surface of the latter at its top, (shown at *c*), the row of contiguous diamond-form ornamentation upon the crown of the dome, (designated at *b*), the rows of ornamental points in revolution around the base of the dome, (designated at *a'*), the band-molding *i*, and the overhanging ring *j*, as shown 110 and described.

6. The design for the ornamentation of the top of the magazine-section of a heating-stove, and consisting of the reversed ovolو molding **O**, arranged in revolution around the top of 120 the section, and having upon its upper and lower edges the waving lines, (designated at *l*), with the molding nickel-plated, as shown and described.

7. The design for the ornamentation of the magazine-section of a heating-stove, consisting of the gray granite color applied to the section, as shown at **C''**, and the nickel-plated panels *m m m*, applied to the section, as shown and described.

8. The design for the ornamentation of the magazine-section of a heating-stove, consisting of the gray granite color applied to the magazine-section, (designated at **C''**), the upper 130

reversed ovolو molding, O, and the base-molding D, having the line of upwardly-projected scallops k'', as shown and described.

9. The design for the ornamentation of the 5 combustion-chamber doors of a heating-stove, consisting of the frame z and the horizontally-curved sash-bar r', the upright sash-bar r'', which, below where it intersects the horizontal bar, is single, and above the intersection 10 branches in two spreading bars to join the top of the frame, as shown and described.

10. The design for the ornamentation of the 15 doors of the combustion-chamber of a heating-stove, consisting of the frame z, horizontally-curved sash-bar r', upwardly-extended and branching sash-bar r'', with vine-leaf projections W W upon the sides of the bars, as shown and described.

11. The design for the ornamentation of the 20 doors of the lower mica section of a heating-stove, and consisting of the frame z'' and the branching sash-bar r⁴, the latter having a single point of attachment at its base, and branching therefrom upwardly in two curved spreading lines to join the top of the frame, and the sash-bar ornamented with vine-leaf projections upon its edge, as designated at r'', as shown and described.

12. The design for the ornamentation of the 25 fire-pot section of a heating-stove, and consisting of the row of zigzag relief figures combined with fan ornaments and arranged around the side of the fire-pot section at its top, (designated at x' x'), the row of zigzag relief figures 30 combined with fan figures upon the side of the section at its bottom, (designated at x'' x''), and the contiguous row of Z-shaped ornaments 35 in revolution around the side of the section at

its center, (designated at x''' x'''), as and described.

13. The design for the ornamentation 45 ornamental form of the sectional foot-rail H, each section having the straight top o¹, the notched and drooping-curtained bottom boundary, o⁵ o⁵, and pendent point o⁶, with a radiant crown produced by intaglio lines upon its exterior face, near the bottom, (designated at n,) and with an intaglio border-line and scrolls upon its outer surface, as shown at t'', and described.

14. The design for the ornamentation shown 50 upon the rearward flue-extension of the stove, (designated at K⁴.) and consisting of a central rosette and surrounding ring in relief, with four intaglio darts radiating from the ring, 55 and four fan figures in relief at right angles to each other and between the darts, as shown at n'', and as herein described.

15. The design for the ornamentation of a 60 heating-stove, consisting of the dome-formed top A, the ornamentation of the magazine-section C, its gray-granite-color relief-panels, and top and bottom moldings in revolution, the form and ornamentation of the doors of the combustion-chamber E, the form and ornamentation of the doors of the lower mica section, F, the ornamentation of the fire-pot section G, and the form and ornamentation of the 65 base I, as shown and described.

Signed at Troy, New York, this 30th day of 70 June, 1880.

GEO. W. GRAVES.
